UNITED STATES PATENT OFFICE.

LUIGI VECCHIO, OF ALBANY, NEW YORK.

COLLAPSIBLE LIFE-BOAT.

1,282,659.

Specification of Letters Patent. Patented Oct. 22, 1918.

Application filed April 20, 1917. Serial No. 163,367.

To all whom it may concern:

Be it known that I, LUIGI VECCHIO, a subject of the King of Italy, residing at Albany, in the county of Albany and State of New York, have invented new and useful Improvements in Collapsible Life-Boats, of which the following is a specification.

This invention is a boat capable of receiving and transporting passengers of 10 larger vessels when the latter are endangered from any cause.

One of the objects of the invention is to produce a boat of simple construction, which may be collapsed when not in use, so as to 15 occupy but little space, and which may be quickly expanded in time of emergency. A further object is to produce a boat of this type which is constructed of very light, but seaworthy material. A further object is to 20 provide means for insuring buoyancy of the boat and to prevent overturning thereof.

The invention will be hereinafter fully set forth and particularly pointed out in the claims.

25 In the accompanying drawings:—

Figure 1 is a plan view illustrating the invention. Fig. 2 is a longitudinal sectional view. Fig. 3 is a detail view illustrating the locking means for the telescoping sections. 30 Fig. 4 is a plan view illustrating the boat collapsed. Fig. 5 is a transverse sectional view illustrating a slight modification.

Referring to the drawing, 10 designates the side bars of the bottom of the main frame, said side bars being of tubular construction, and held in spaced relation by a transverse bar 11, attached thereto in any suitable manner. Said side bars are provided with upright tubular extensions 12, 35 into which extend smaller telescoping members 13 attached to the upper side bars 14. When the bars 14 are in their raised position, the members 13 are engaged by spring locking devices 15, to prevent collapsing 40 thereof.

Telescoping with the side bars 10, are the arms of approximately U-shaped end frames 16, each provided with tubular uprights 17, which telescope with reduced members 18 attached to upper end frames 19, telescoping 45 with the ends of the side bars 14. The frames 16 are locked in extended relation by means of spring catches 15, similar to those already described, and similar catches also 50 serve to lock the telescoping members 17 and 18 in extended relation. Covering the

frames is a body 20, preferably of canvas, or any other suitable material possessing the necessary waterproof and wear-resisting properties, the edges of the fabric being secured to the top frames in any desired manner. Secured to the frames 16 are bars 21, of substantially V-shape, with the point of the angle extending toward the center of the boat. The bars 11 and 21 are provided 55 with downturned projections 22, to which are secured floats 23, of suitable buoyant material such as cork, the size and number of the floats being determined by the number of passengers which the boat is designed to 60 carry. It will be readily understood from the drawings, that each rod is provided with three floats or sets of floats, one being located beneath the middle of the boat, and the other two beyond the sides thereof. By this arrangement ample buoyancy is provided and the floats are so positioned as to resist overturning of the boat.

In practice, the parts are normally collapsed as illustrated in Fig. 4, the end 65 frames being moved inwardly to the limit of their movement, the top frames being moved downwardly to the limit of their movement, the fabric forming the body of the boat being folded, as shown. In this manner the 70 boat occupies but little space. When it is desired to use the same, the end frames are drawn outwardly until movement is arrested by the spring catches 15, and the upper 75 frame is moved upwardly to the limit of its 80 movement, whereupon the boat is ready for occupancy.

In Fig. 5 I have shown a slight modification designed to increase the capacity of the boat. In this form the frames heretofore 85 described are made much larger, and the upright bars 12 are provided with hooks to be engaged by straps 24, which in turn are engaged by hooks attached to bars 25 supporting a flexible canvas floor 26. Said 90 floor is further supported by means of stays 27 attached thereto and to hooks 28 carried by the bars 13 and 18. If desired a roof 29 may also be provided, the same being held in place by suitable hooks attached to 95 the top frame bars. By this arrangement a number of passengers may be placed in the bottom of the boat, and others may be carried by the floor 26. Of course, the floats 23 are made sufficiently large to provide the 100 necessary buoyancy.

Having thus explained the nature of the

invention, and described an operative manner of constructing and using the same, although without attempting to set forth all of the forms in which it may be made, or 5 all of the forms of its use, the following is claimed:—

1. A collapsible life boat comprising a main frame composed of vertically spaced straight tubular top and bottom members 10 open at both ends, and rigid end frames having top and bottom bars telescoping within the open ends of said tubular members, said end frames preventing relative lateral movement of the top and bottom members at all 15 times, a flexible water-proof body secured to said frames, and floats connected with the frames.

2. A collapsible life boat comprising a main frame composed of vertically spaced 20 straight tubular top and bottom members open at both ends, and rigid end frames having U-shaped top and bottom bars telescoping with the open ends of said tubular members, said end frames preventing relative lateral movement of the top and bottom members at all 25 times, a flexible water-proof body secured to said frames, and floats also connected with said frames.

3. A collapsible life boat comprising a bottom frame having tubular side members 30 open at both ends, means for preventing relative lateral movement of said frames, rigid end frames having bottom bars telescoping with the open ends of said side members, 35 sectional top frames vertically adjustable with respect to said tubular side members and with respect to the end frames, a flexible

water-proof body secured to all of said frames, and floats attached to the bottom and end frames.

4. A collapsible life boat comprising a bottom frame having tubular side members open at both ends and provided with upright members, means for preventing relative lateral movement of said side members, 45 rigid end frames having members telescoping within the open ends of the side members and also provided with upright members, sectional top frames having depending members telescoping with the upright members, 50 a flexible water-proof body attached to all of said frames, and floats attached to the bottom and end frames.

5. A collapsible life boat comprising a middle frame, end frames adjustably connected therewith, cross bars secured to the respective frames and having downturned 55 projections, floats secured to said projections, and a flexible waterproof body attached to said frames.

6. A collapsible life boat comprising a collapsible bottom frame, a collapsible top frame adjustably connected therewith, a flexible waterproof body secured to said frames, floats connected with said frames, 60 a temporary floor, and means connected with said frames for supporting said floor.

In testimony whereof I have hereunto set my hand in presence of two subscribing witnesses.

LUIGI VECCHIO.
